UNITED STATES PATENT OFFICE.

WILLIAM E. FAHRNER, OF MCKITTRICK, MISSOURI.

PUMP-CHAIN.

1,240,550.

Specification of Letters Patent. Patented Sept. 18, 1917.

Application filed November 4, 1916. Serial No. 129,572.

To all whom it may concern:

Be it known that I, WILLIAM E. FAHRNER, a citizen of the United States, residing at McKittrick, in the county of Montgomery 5 and State of Missouri, have invented certain new and useful Improvements in Pump-Chains, of which the following is a specification.

This invention relates to an improved 10 type of pump chain and the primary object is to provide a flexible chain for elevating water from a well to a point above the surface of the ground at the same time causing air to be circulated through the water for 15 purifying the same and preventing the water from becoming stagnant.

As a further object of the invention the pump chain is provided with buckets of two distinct types, certain of the buckets of one 20 type being connected together and having their ends connected to buckets of the other type.

A further object of this invention is the provision of a pump chain which consists of 25 comparatively few parts and is simple in construction, but durable and well adapted to withstand the rough usage to which devices of this character are ordinarily subjected.

30 For a full description of the invention and the advantages and merits thereof, reference is to be had to the following description and the accompanying drawings, wherein is illustrated the preferred form of my invention, in which;

Figure 1 is an elevation of a portion of the pump chain constructed in accordance with my invention.

Fig. 2 is a longitudinal section there- 40 through.

Referring to the drawing, wherein is illustrated the preferred form of my invention, and in which like numerals of reference indicate corresponding parts throughout the 45 several views, it will be noted that two elements of the chain are disclosed in each figure of the illustration of the invention. It will be understood, of course, that the chain will consist of a plurality of link members 50 forming a continuous chain for passing over a spoked wheel situated above the ground in the usual manner while the lower portion of the chain will be submerged in the water of the well. Thus, when the spoked wheel is 55 rotated the links of the chain will be raised

and lowered for raising the water from the well and for conveying air to the water in the well.

In the present invention, two types of links A and B are employed to constitute the 60 chain. The link A comprises a cylindrical cup 1 having a closed end 2 and an open end 3. Integrally formed with the edge of the open end of the cylindrical cup is a plurality of converging retaining arms 4 welded 65 or otherwise fastened to a central rod 5 extended longitudinally through the cup 1. The converging retaining arms 4 are extended inwardly at an angle from the edge of the cup and serve to retain the cup in rigid position and prevent collapsing of the same when the chain is in operation. Both the meeting ends of the retaining arms 4 and rod 5 is extended and bent to provide the connecting hook 6 which is adapted to be received in the loop of the adjacent link when the chain is entirely assembled. The lower end of the central rod 5 is provided with a circular eye 7 having a portion disposed beyond the closed end 2 of the cup. This construction is obtained by providing the closed end 2 with oppositely disposed openings through which opposite sides of the loop 7 are extended after which the loop is soldered or otherwise fastened to the closed end 2 for 70 preventing leakage through the joint thus formed.

The type B of the links comprises a connecting rod 8 which is similar in construction to the central rod 5 employed in the 90 above described link. One end of the rod 8 is provided with a loop 9 for receiving the eye 7 of the link A and the opposite end of the rod has the eye 9, identical in construction with the eye 7 of the link A. In 95 this instance, however, the lifting bucket comprises a circular disk 10 of rubber or other such similar material. Mounted upon the rod 8 and resting against the eye 9 is a spacing disk 11 adapted to fit into the concaved side 12 of the disk 10 and have one of its surfaces contacting therewith whereby the disk 10 will be held at the proper point upon the rod 8 so that the disk will not strike any of the teeth or spokes of the 100 pump wheel (not shown). The opposite side of the disk 10 is convexed and contacts with a nut 13 mounted upon the rod 8. An annular groove 14 is formed in the edge 105 of the disk thereby providing a double lip 110

for contacting with the inner wall of the pump tubing (not shown).

It will be understood that these links may be made up into a chain having a cup link A 5 in each alternate position in the chain with the links B interposed therebetween. The links may be arranged in any preferred manner and when assembled the bucket links B will cause the water to be quickly 10 drawn through the tubing in the pump while the cups of the links A will also carry a certain amount of water to the top of the pump. The cups 1 of the links A, however, perform the additional function 15 of carrying air into the water where it is permitted to circulate and rise to the surface of the water in the well thereby purifying the same since it is well known that the oxygen contained in the air possess purifying qualities for water.

From the foregoing it will be observed that a very simple and durable pump chain has been provided, the details of which embody the preferred form. I desire it to be 25 understood however, that slight changes in the minor details of construction may be made without departing from the spirit of the invention or the scope of the claims hereunto appended.

Copies of this patent may be obtained for five cents each, by addressing the "Commissioner of Patents,
Washington, D. C."

I claim:

1. A pump chain comprising a plurality of connecting rods having their ends linked together, cups mounted upon certain of the said connecting rods including hollow cylindrical member each provided with closed ends, the loop at the end of the said connecting rod being partially extended through the said closed end, and retaining arms at the open end of the cup secured to the said connecting rod.

2. A pump chain comprising a plurality of rods linked together at their ends, certain of said rods carrying cups each of which comprises a hollow cylindrical member provided with a closed end having openings formed therein, the end of the corresponding connecting rod adjacent the closed end of each cup being provided with an eye having its opposite portions extended through the said openings, and retaining arms integrally formed with each cup and connected to the corresponding rod.

In testimony whereof I affix my signature in presence of two witnesses.

WILLIAM E. FAHRNER.
